(57) **CLAIM**

The ornamental design for a gaming simulator frame, as shown and described.

DESCRIPTION

FIG. 1 is a top view of a gaming simulator frame in a first operable configuration;

FIG. 2 is a bottom view of a gaming simulator frame in a first operable configuration;

FIG. 3 is a first side view of a gaming simulator frame in a first operable configuration;

FIG. 4 is a second side view of a gaming simulator frame in a first operable configuration;

FIG. 5 is a front view of a gaming simulator frame in a first operable configuration;

FIG. 6 is a rear view of a gaming simulator frame in a first operable configuration;

FIG. 7 is an upper front perspective view of a gaming simulator frame in a first operable configuration;

FIG. 8 is a lower front perspective view of a gaming simulator frame in a first operable configuration;

FIG. 9 is an upper rear perspective view of a gaming simulator frame in a first operable configuration;

FIG. 10 is a lower rear perspective view of a gaming simulator frame in a first operable configuration;

FIG. 11 is a top view of a gaming simulator frame in a second operable configuration;

FIG. 12 is a bottom view of a gaming simulator frame in a second operable configuration;

FIG. 13 is a first side view of a gaming simulator frame in a second operable configuration;

FIG. 14 is a second side view of a gaming simulator frame in a second operable configuration;

FIG. 15 is a front view of a gaming simulator frame in a second operable configuration;

FIG. 16 is a rear view of a gaming simulator frame in a second operable configuration;

FIG. 17 is an upper front perspective view of a gaming simulator frame in a second operable configuration;

FIG. 18 is a lower front perspective view of a gaming simulator frame in a second operable configuration;

FIG. 19 is an upper rear perspective view of a gaming simulator frame in a second operable configuration; and,

FIG. 20 is a lower rear perspective view of a gaming simulator frame in a second operable configuration.

The broken lines in the drawings depict portions of the gaming simulator frame that form no part of the claim.

1 Claim, 20 Drawing Sheets
